UNITED STATES PATENT OFFICE

PAUL A. HAUENSTEIN, OF BUFFALO, NEW YORK, ASSIGNOR TO VIMCO MFG. CO. INC.,
OF BUFFALO, NEW YORK

ADJUSTABLE LAMP BRACKET OR SUPPORT

Application filed September 26, 1929. Serial No. 395,322.

This invention relates to improvements in portable adjustable lamp or light supports, brackets or devices, such as are used, for example, for attaching or supporting an electric light, on or in operative relation to machines of different kinds, such as typewriters and other writing or printing machines, dictaphones and the like. Certain features of the invention are applicable to brackets for supporting lights for more general use, such as upon beds or other articles of furniture and in other places where a portable light may be required.

Some objects of the invention are to provide a portable, adjustable lamp support or bracket of simple and rugged construction which when mounted in place, permits the lamp to be adjusted to various operative positions; also to provide a bracket of this kind which is constructed to permit the lamp carried thereby to be moved from an operative to an inoperative position and vice-versa; also to provide a support or bracket of this kind comprising a plurality of articulated joints or sections which are readily movable to and held in different relative angular relations one to another; also to provide an articulated bracket or support with pivotal connections or joints of novel construction; also to provide the bracket with improved clamping means for securing the bracket to different articles; also to provide improved adjusting means permitting the clamp to be attached to articles of different sizes or forms; also to provide improved connections between the articulated sections of the bracket and said clamp and also between one of said sections and a lamp socket; and also to construct a lamp bracket of this kind having one or more hollow joints or sections through which the electric conductor for the light passes and to provide joints between said section or sections and the other parts of the bracket, which permits free passage of the conductor through said hollow section or sections.

More specific objects are to construct a lamp bracket of neat and attractive appearance which can be attached to a typewriter or the like so that the lamp can be disposed

above and illuminate the same, and which can be folded down close to the top or frame with the lamp extending into the recess into which the type keys are disposed; and also to construct a bracket for this purpose having a relatively small and inconspicuous attaching part which extends close to the side of the machine.

Other objects are to improve lamp supporting brackets or devices in the other respects hereinafter set forth and claimed.

In the drawings:

Fig. 1 is a front elevation showing an embodiment of my improved adjustable lamp supporting bracket applied to a portable typewriting machine;

Fig. 2 is a fragmentary front elevation thereof, partly in section, showing the adjustable clamp thereof in operative relation to the frame of a typewriting machine;

Fig. 3 is a vertical section of the parts shown in Fig. 2, on an enlarged scale;

Fig. 4 is a side elevation of the lamp bracket and a part of the typewriting machine shown in Fig. 1;

Fig. 5 is a side elevation, on an enlarged scale, of a connecting plug or member of the adjustable bracket;

Fig. 6 is a face view of one of the tubular joints or sections of the bracket, detached;

Fig. 7 is a vertical section, on an enlarged scale, of the connection between the lamp socket and one of the joints or sections of the bracket;

Fig. 8 is a side elevation of a modified construction of the adjustable lamp bracket;

Fig. 9 is a vertical section thereof, on line 9—9 Fig. 8, on an enlarged scale, showing the means for attaching the same to a machine or other article.

Figs. 1 to 6 of the drawings illustrate what I consider at present to be a preferred embodiment of my invention. In this construction the adjustable lamp bracket comprises three relatively adjustable or movable sections, connected end to end, thereby providing two outer sections and one intermediate section. One of the outer sections is formed for attachment to the article on which the

bracket is to be mounted, while the other outer section is secured directly to the socket of the lamp. The intermediate section has pivoted or articulated connection with the two outer sections, thus enabling the lamp to be placed in different relative positions to the article to effect the desired illumination thereof.

The intermediate section is designated generally by the numeral 10 and the upper and lower outer sections by the numerals 11 and 12 respectively.

The intermediate section 10 preferably comprises an elongated tube or sleeve formed as shown in Fig. 6, of a single piece of sheet metal bent to a substantially cylindrical form and having opposite outer ends or attaching portions 14 and 15, each of which is preferably extended laterally with reference to the bore of the section 10 and is of cupped or concaved form, see Fig. 3. The attaching portions 14 and 15, each have pivotal connection with complementary parts enabling the section 10 to swivel or turn relative to the outer sections of the bracket. For example, the lower attaching portion 15 is received in a complementary cupped or concaved lug 17 of a connecting member 18, and these parts 15 and 17 are formed with registering central holes 19 and 20 respectively, for the reception of a rivet or other securing device 21. One head 22 of the rivet 21 is confined within and bears against the concaved inner face of the attaching portion 15, while the other head or enlargement 23 of said rivet bears against a spring disc or washer 24, the peripheral edge of which is turn frictionally engages the convex outer face of the lug 17 with sufficient pressure to hold the section 10 in any position relative to the part 18 to which it may be adjusted.

The upper attaching part 14 of the section 10 is similarly pivoted on and frictionally held against a concaved lug 25 on a connecting part 26, by means of a rivet 27 and spring washer or disc 28.

By making the engaging faces of the attaching parts 14 and 15 and the corresponding lugs 17 and 25 of curved formation, as described, the area of contact and friction between these parts is increased, as compared with corresponding flat faces, and the parts are also considerably strengthened. In addition this construction enables the inner heads of the rivets 21 and 27 to be largely concealed or confined in the concavities of the respective parts 14 and 15.

The connecting part or member 18, before mentioned, is provided with an angularly related disc or swivel portion 30 having a central aperture 31 in which the upper end 32 of a swivel plug or member 33 is received. The plug 33 is provided with an annular shoulder or enlargement 34 against which the disc 30 is held by an outwardly flaring bead

or edge 35 of the part 32 of said plug 33. There is sufficient clearance between the two parts 34 and 35 of the plug and disc 30 to permit the latter to be rotated about said plug.

The plug 33 is provided at the opposite side of the shoulder 34 with a reduced cylindrical part 38 formed to have a driving or tight fit in or is otherwise rigidly secured to the upper end of a cylindrical sleeve or tubular member 40.

The lower outer section 12 of the bracket is preferably formed of two parts which are relatively movable lengthwise, each part being provided or associated with a jaw or the like for engagement with opposite faces or parts of the machine or other article to which the bracket is to be attached, suitable adjusting means being provided to vary the distance between said jaws.

In the construction shown for this purpose, the section 12 comprises the sleeve or member 40 and a second part 41 preferably in the form of a rod which telescopically engages in said sleeve 40. The rod or part 41 is provided at its lower end with a lateral jaw or extension 42 which, if desired, may be cut away on its upper face to form a seat 43 for engagement with one part of the article.

A second jaw or lateral extension 45 is operatively associated with the upper tubular part 40 of the section 12, being, in the construction shown, provided with an apertured part 46, which is rigidly secured or gripped between the lower face of the shoulder 34 and the upper end of said sleeve 40. This jaw 45 engages another part of the article to which the bracket is to be attached and cooperates with the lower jaw 42 in holding the bracket securely in place on the article when the jaws are forced tightly against the same.

The jaw or extension 45 may have various different formations, for example, as shown in Figs. 2 and 3, this part is curved to fit the correspondingly curved part of the machine or article which it engages, while, as shown in Fig. 1 this part of the arm is straight so as to properly engage the adjacent flat face of the typewriter frame shown in that figure.

Any suitable means may be provided for effecting relative adjustments between the jaws 42 and 45. In the construction shown, the rod or part 41 of the section 12 is bored and threaded axially at 47 for the reception of the threaded shank 48 of an adjusting screw 49, which is rotatably mounted in a bore in the plug 33. The head 50 of this screw bears on the outer end or bead 35 of the plug 33, so that by turning said screw in one direction or another, the parts 40 and 41 of the section 12 and the corresponding jaws 42 and 45 can be adjusted as required.

By this construction it will be seen that the supporting bracket may readily be attached

to articles of various forms and dimensions by appropriate adjustments of the clamping jaws of the section 12, and since the intermediate section 10 is connected thereto by the part 18 which is swiveled to the section 12, in horizontal plane and to the section 10 in a vertical plane, the latter section may be rotated about the axis of and adjusted to any desired angular relation to the section 12.

10 The connection between the member 26 and the lamp socket A is effected in a somewhat similar manner to the connection between the part 18 and the lower section 12. This connection includes a plug or member 52 provided with an annular shoulder 53 and a turned over portion 54 between which a lateral extension 55 of the member 26 is secured. In this case however, said part 55, instead of having relative movement with 20 said plug 52, is pinched or rigidly secured between the parts 53 and 54 so as to prevent axial rotation of the lamp socket relative to the part 26. The lamp socket A is of the usual construction provided with a standard internally threaded end or part 56, and the plug 52 is threaded at 57 and operatively engages in said part 56 of the socket.

25 The usual electrical cord or conductor *a* passes from the lamp socket A outwardly through a central bore 58 in the plug 52 and downwardly through the hollow intermediate section 10 of the bracket, thence passing directly to a plug or other electrical connection, thus being substantially concealed and 30 confined within the bracket above the lower section 12 thereof.

35 It will be noted upon reference to Figs. 3 and 7 that since the pivotal connections at the opposite ends of the section 10 are offset, and the heads of the respective rivets 21 and 40 27 are located well within the concavities of the respective parts 14 and 15 of said section, these rivets or pivotal connections do not obstruct the free passage of the electric 45 cord or conductor *a* in the various adjustments of the bracket.

40 It will be seen from the foregoing description that the lamp supporting bracket or device can be easily and quickly adjusted and secured on articles of various sizes and shapes 50 and that the lamp and its socket A can be readily adjusted to different positions through its pivotal connection with the articulated section 10 of the bracket.

55 The attaching section 12 being of elongate form and telescopic construction can be disposed close to the machine or article, will project but little therefrom and is inconspicuous. Also the adjusting screw being 60 concealed within this section, does not detract from the appearance of the bracket or the article upon which the latter is mounted.

65 A bracket or device of this character, while of use for supporting lamps for widely different purposes, is nevertheless particularly

adapted for supporting or attaching a lamp to a typewriting machine or other writing or printing machines. When the bracket has once been attached to the typewriter or other machine it can remain thereon and be transported with the machine from place to place without detaching the bracket from the machine, and when the machine is not in use the lamp can be moved to a position within the usual concavity or recess of the machine 70 as illustrated in dotted lines in Fig. 1. In the case of standard typewriting machines for example, the intermediate section 10, due to the location of the pivotal connections 21 and 33 close to the upper clamping jaw 45, 80 can extend or be folded closely against the upper face of the machine or article, and the lamp is protected from damage and permits the usual cloth or fabric dust cover or protector to be placed over the machine. 85 In the case of a portable machine, this feature permits the lamp and its bracket to remain attached thereto, and when not in use the lamp occupies a position within the aforementioned space in the machine and 90 permits the cover or case of the machine to be secured in place without interfering with or engaging the lamp.

95 The described construction permits the lamp supporting bracket to be formed of relatively simple and inexpensive parts which can be readily assembled. For example, the lower or clamping section 12 may be assembled by first driving or otherwise fitting the plug 33 into the upper end 100 of the sleeve 40 with the upper jaw or clamp 45 disposed between the shoulder 34 of said plug and end of said sleeve, after which the lateral extension 30 of the attaching part 18 is applied over the upper end of said plug, 105 which at this time is formed as shown in Fig. 5. The upper end of the plug 33 is then swaged or flared outwardly over said part 30 to form the retaining bead 35. The rod 41 of the section 12 now inserted into the lower end of the sleeve 40 and the adjusting screw 49 is extended downwardly 110 through the bore in the plug 33 and operatively engaged in the threaded aperture in said part 41.

115 It may at times be desirable to permanently attach a lamp bracket of this character to an article, in which case the two part adjustable clamping section 12 can be omitted and other means of simpler form substituted therefor.

120 For example as shown in Figs. 8 and 9, the attaching member 18 at the lower end of the intermediate section 10 has a lateral lug 60 which is pivotally secured by a rivet or other fastening device 61 to an offset extension or lug 62 of a bracket 63. This bracket may be formed of sheet metal, having a depending attaching portion 64, which is apertured at 125 65 for the reception of a fastening screw or 130

device 66 by which it is attached directly to the article on which the bracket is to be permanently secured.

In Fig. 8 the bracket is shown as attached to an upright side wall of a portable typewriting machine adjacent its top face, so as to permit all of the adjustments for the lamp which may be had by the use of the bracket shown in Fig. 1, and whereby the bracket can be folded adjacent the top of the machine with the lamp in the recess therein as before.

Any other suitable attaching member or means may be substituted for the bracket 63 for permanently securing the lamp support to an article.

Claims:

1. A lamp bracket including a section at one end of which a lamp is supported, an attaching section at the other end of said section comprising a tubular member, a second member formed to telescope therein for movement lengthwise thereof, a plug fixed in and extending axially of said tubular member, an adjusting device extending axially through the same and into said member and operatively engaging said movable member for telescopically adjusting the latter, and a pivotal connection between said attaching section and said other section including an attaching part swiveled on said plug so as to rotate axially thereon and having a part extending therefrom and which is pivotally attached to the adjacent end of said other section.

2. A bracket for adjustably mounting a lamp upon a typewriter having a top face and a recess therein below the plane of the top of the machine in which the type keys are disposed, said bracket including an intermediate section at one end of which a lamp is pivotally supported, an attaching section for securing the bracket to said typewriter, and a pivotal connection between the latter and said intermediate section which, when said bracket is in operative position is disposed close to said top face of said typewriter to permit the intermediate section to be folded down so as to extend across and lie close to said face, and said intermediate section being of such length as to permit the lamp at the other end thereof to be adjusted so as to extend within the recess of said typewriter and below the plane of said machine top, whereby said bracket can be left attached to and carried on said typewriter when the latter is moved from one place to another, and whereby protection is afforded said lamp by its location in said recess.

3. A bracket for adjustably mounting a lamp upon a typewriter having a frame including a top face and a recess therein below the plane of said frame top in which the type keys are disposed, said bracket including a section at one end of which a lamp is

pivottally supported, an attaching section for securing the bracket to said typewriter frame, said attaching section being of elongate form extending close to a side of said typewriter, and which includes two members 70 which telescope one within the other, a clamping part on each of said members one of which engages said top face of said typewriter, means for adjusting the other clamping part on said frame towards and from 75 said first part to secure said section on the typewriter, and a pivotal connection between said attaching section and said other section which, when said attaching section is clamped in position, is disposed close to said first clamping part to permit said other section to be folded down so as to extend across and lie close to said top face of said typewriter with said lamp extending into said recess below the plane of said top of said typewriter, whereby the bracket can be left attached to said typewriter and be carried therewith while the lamp is protected by its position within the frame of the typewriter.
